DENTAL JET PRODUCING UNIT

Samuel J. Koch, 999 Green St.,
San Francisco, Calif. 94133

Filed July 12, 1967, Ser. No. 7,769

Term of patent 14 years

(Cl. D24—1)

FIG. 1 is a perspective view of a dental jet producing unit showing my new design.

FIG. 2 is a side view thereof, the broken lines showing the position of a nozzle member.

FIG. 3 is a rear view thereof.

FIG. 4 is a top view thereof.

FIG. 5 is a bottom view thereof.

The dominant features of my design reside in the portions shown in full lines. The portions shown in broken lines in FIG. 2 are omitted in the other figures for convenience of illustration.

I claim:

The ornamental design for a dental jet producing unit, substantially as shown and described.
